UNITED STATES PATENT OFFICE.

ROLAND J. FAIRCHILD, OF KALAMAZOO, MICHIGAN, ASSIGNOR TO NATIONAL WATER LIFT COMPANY, OF KALAMAZOO, MICHIGAN.

PISTON PUMP.

Application filed November 19, 1925. Serial No. 70,056

This invention relates to an improvement in piston pumps particularly designed for use in supplying air in compression air tank water systems.

5 An object of the invention is to provide a very simple structure which will insure delivery of air along with the water to maintain the air supply in the compression tank.

10 A further object is to provide an improved construction of valve in such combination, and a still further object is to provide an improved arrangement of pump valves in that relation, to insure its efficiency.

15 Objects pertaining to details and economies of construction and operation will definitely appear from the detailed description to follow.

20 I accomplish the objects of my invention by the devices and means described in the following specification. The invention is clearly defined and pointed out in the claims.

25 A structure which is a preferred embodiment of my invention is clearly illustrated in the accompanying drawing, forming a part of this application, in which:

Fig. 1 is an elevation view of a pump embodying the features of my invention, the driving means being omitted.

30 Fig. 2 is an enlarged detail elevation view taken from the right hand of Fig. 1, the pump itself being sectioned on line 2—2 of Figs. 1, 3 and 4.

35 Fig. 3 is an enlarged detail sectional view taken on the angular broken line 3—3 of Figs. 2 and 4.

Fig. 4 is an enlarged detail sectional view through the pump on the broken plane indicated by the line 4—4 of Figs. 2 and 5.

40 Fig. 5 is a detail sectional view taken on line 5—5 of Figs. 2 and 4.

Fig. 6 is an enlarged detail vertical sectional view through the air intake valve mechanism taken on line 6—6 of Fig. 7.

45 Fig. 7 is an enlarged detail transverse sectional view taken on line 7—7 of Figs. 1, 4 and 6.

Fig. 8 is an enlarged detail view from the right side of the spacer washer of Fig. 6 of the air intake valve mechanism.

50 In the drawing similar reference characters refer to similar parts throughout the several views, and the sectional views are taken looking in the direction of the little arrows at the ends of the section lines.

The parts of the drawings will be referred to by their numerals of reference. 1 is the supporting base, 2 the complete pump cylinder, 3 are the bolts attaching it to the base, 4 is the stuffing box, 5 is the hydraulic pump piston, and 6 is the piston rod for the same, all of usual design. The pump is double acting. The head 7 screws into the cylinder, and has a gasket 8 of usual construction. The head is extended into an axially centrally-disposed valve chamber 9, 65 within which is disposed a hydraulic cup pump packing constituting the valve.

The pump packing is held in place by the screw 11 from the inside. The valve chamber 9 has an axial externally screw-threaded 70 extension 91 flattened at 92. The screw cap 12 is adjustable thereon to vary the size of the passage. An internal screw thread 93 is provided for the screw 11, cut away at 110 to form an air passage therethrough, so that 75 there is an air passage around the edge of the cap 12 through the opening into the cap through the opening 110 into the valve chamber, thence past the yielding valve 10 into the cylinder. A spacer washer 111 with 80 notched annular rib 111' is disposed on the screw 11 within the valve casing 9. These parts fit very closely and any air drawn in is at once stopped and forced on through the pump.

85 The pump connects to the suction pipe 14 and is provided with an air chamber 15. The intake manifold 13 connects with the suction pipe 14. The valve casings 16 are slightly inclined and the valves 17 are in 90 slightly inclined relation from the vertical on their seats and are held in place by springs 18, so that a very slight opening permits the water to deliver up quickly into the cylinder. The usual valves 20 are provided on 95 the discharge side of the pump, delivering the water to the delivery pipe 21. The air is preferably delivered through the air pipe 22 to the air chamber of the tank.

I desire to state that my improved air valve 100 structure can be used with various kinds of water pumps, but the pump structure here shown is especially adapted to that end. I therefore desire to claim the structure specifically as here illustrated, and also the air 105 intake combination broadly, as pointed out in the appended claims.

Having thus described my invention, what

I claim as new and desire to secure by Letters Patent is:

1. An air valve for a hydraulic pump comprising a cylindrical casing, a hydraulic packing within said cylinder constituting the valve, an extension to the said casing, a screw threaded outside and inside and flattened on one side, a screw flattened on one side for retaining said hydraulic packing 10 valve in position, and a screw cap over said screw threaded extension for adjusting the

size of the aperture therethrough, as described.

2. An air valve for a hydraulic pump comprising a cylindrical casing, a hydraulic packing within said cylinder constituting the valve, and a screw flattened on one side for retaining said hydraulic packing valve in position, as described.

In witness whereof I have hereunto set my hand.

ROLAND J. FAIRCHILD.
